UNITED STATES PATENT OFFICE.

JOSEPH A. BOZUNG AND PATRICK S. McMAHON, OF DENVER, COLORADO.

DOUBLE COMPOUND POWER-APPLYING MACHINE.

1,392,295.

Specification of Letters Patent.

Patented Oct. 4, 1921.

Application filed January 13, 1920. Serial No. 351,202.

To all whom it may concern:

Be it known that we, JOSEPH A. BOZUNG, formerly a citizen of Germany, but who has declared his intention of becoming a citizen 5 of the United States of America, and PATRICK S. McMAHON, a citizen of the United States of America, both residing at the city and county of Denver and State of Colorado, have invented a new and useful Double 10 Compound Power-Applying Machine, of which the following is a specification.

Our invention relates to improvements in double compound power applying machines.

The object of the invention is to provide 15 a machine or device of this character in which power is applied to a pawl and ratchet mechanism through a series of levers acting one upon another in progressive order, the initial power exerted upon the 20 first lever of the series being transmitted through the succeeding levers to the pawl and ratchet mechanism, said mechanism being arranged to rotate a power shaft from which power may be transmitted through a 25 system of gearing and applied in any desired manner.

Further, to provide a power machine of this character in which the initial power may be manually applied to the first lever 30 of the series, or the said lever may be connected to power driven operating mechanism.

These objects are accomplished by the mechanism illustrated in the accompanying 35 drawings in which:

Figure 1 is a side elevation of the machine looking toward the initial operating lever.

Fig. 2 is a side view at right angles to Fig. 1 and looking toward the second lever 40 of the series.

Fig. 3 is a plan view of the machine.

Fig. 4 is an enlarged sectional view on the line 4—4 of Fig. 3, illustrating the pawl and ratchet mechanism.

Fig. 5 is a plan view of the parts illustrated in Fig. 4, and

Fig. 6 is a perspective view of one of the links which connect the end of one lever with that of the succeeding lever.

Referring to the accompanying drawings: The numeral 1, indicates the base of the machine which comprises a horizontal plate upon which the power mechanism is mounted, the plate being provided with bolt holes 50 2, through which securing bolts may be passed to rigidly secure the plate to a fixed

support. The plate is provided with posts or standards which may, if desired, be secured thereto, but which preferably form an integral part of the plate. The standards 60 are arranged in three groups, as follows: the lever supporting standards 3, 4, and 5; the power shaft supporting standards 6, the power-receiving shaft standards 7, the power-transmitting shaft standard 8, and 65 the standards 9, which support a power driven shaft which operates the initial lever of the series.

The initial lever 10, is a lever of the first class, or one in which the fulcrum is between the weight and power, and is mounted on a fulcrum pin 11, in the upper end of the standard 3, which is bifurcated to receive the said lever, and the ratio of the distance between the fulcrum and weight end of the 75 lever, to the distance between the fulcrum and the power end thereof, may be determined by the use for which the machine is employed.

In the drawing, the long end of the lever 80 is shown as being less than three times the length of the short end, or of a ratio to the short end of less than three to one; but the fulcrum, in any case, will be positioned to meet power requirements. This lever may 85 be manually operated, if desired, but, in the drawings, it is shown as power driven, and is connected with a source of power in the following manner:

The power end of the lever 10, is provided with a longitudinal slot 12, through which passes a wrist pin 13, in the outer end of a crank 14, which is rigidly secured upon one end of a shaft 15, which is mounted in bearings on the standards 9. 90

The shaft 15, carries a pulley 16, which is connected by a belt 17, with a suitable power source (not shown), by which the shaft 15, is rotated, and an oscillating movement is thereby imparted to the lever, the 100 wrist pin 13, sliding from one end of the slot 12, to the other as the crank 14, rotates.

The weight end of the lever 10, is connected by a link 18, with the power end 105 of a second lever 19, which is pivotally mounted on a fulcrum pin 20, in the upper end of the standard 4, which is bifurcated to receive the said lever 19.

For convenience and compactness, the 110 lever 19, is arranged to lie at right angles to the lever 10, and as shown, the distance

between its fulcrum and weight end bears the same proportion to the rest of the lever, as the corresponding parts of the lever 10, bear to each other, but with this lever, as with the lever 10, the fulcrum may be at any desired point between its ends.

The ends of the levers 10 and 19, which are connected by the link 18, are formed with elongated holes 21, and 22, respectively, 10 to receive the pins 23 and 24, respectively, which connect the ends of the levers with the link, and as the link is limited to a vertical movement, while, at the same time, the ends of the levers travel in arcs, it is 15 apparent that the link would be bent or broken by the levers, but for the elongated holes 21, and 22, which allow sliding movement of the ends of the levers on the pins 23 and 24, as will be seen by reference to 20 Figs. 1, and 2.

The link 18, is of the form shown in Fig. 6, and comprises a central body portion and bifurcated end portions which are apertured, as shown, to receive the pins 23 and 24, the bifurcations being arranged 25 at right angles to each other.

The links hereinafter mentioned, are of the same construction as the link 18, and therefore need no description, and in all 30 cases the levers are provided with elongated holes to receive the link pins.

The weight end of the lever 19, is connected to the power end of a lever 25, by a link 26, and this lever is mounted on a 35 fulcrum pin 27, in the upper end of the standard 5, the fulcrum pin being approximately the same proportionate distance from the power end of this lever, as in the levers 10 and 19.

40 Depending links 28, are pivotally connected to the lever 25, one of which depends from the free or weight end of said lever, while the other is located between the fulcrum and the power end thereof, 45 and the same distance from the fulcrum as the other link.

The links 28, are connected at their lower ends, to the free ends of a pair of levers 29, the opposite ends of which are bifurcated and are loosely mounted on a power shaft 30, which is mounted in bearings on the upper ends of the standards 6. Within the bifurcated end of each lever 29, and rigidly mounted on the shaft 30, is a group 55 of ratchet wheels 31, each group comprising, preferably, four ratchet wheels. Each of these wheels is provided on each side with a slight circular projection 32, and these projections serve to space the tooth portions of the wheels, as will be understood by reference to Fig. 5. These wheels are keyed upon the shaft in such relation to one another that the teeth of the second wheel in each group, are slightly out of 60 line with those of the first wheel; the teeth 65

of the third wheel, are slightly out of line with those of the second wheel, and the teeth of the fourth wheel, are slightly out of line with those of the third and first wheels, the order being progressive from 70 the first to the fourth wheel.

A pin 33, extends through the bifurcated portion of each lever 29, and upon each pin are mounted four pawls 34, one pawl of each group being always in engagement with a 75 tooth of one of the ratchet wheels. The pawls of each group are held in engagement with the ratchet teeth, by a plate spring 35, which is screwed to the lever 29, as shown, the forward end of each plate being slotted 80 to form four independent fingers 36, which rest upon, and hold the pawls against the ratchet teeth, as clearly shown in Figs. 4 and 5.

Power from the shaft 30, is transmitted in 85 the following manner:

A gear wheel 37, is rigidly mounted on the said shaft 30, and this gear wheel meshes with a gear wheel 38, of suitable diameter, which is rigidly secured upon a shaft 39, 90 which is mounted in bearings on the upper ends of the standards 7. The shaft 39, has also secured thereon a bevel gear 40, of greater diameter than the gear 38, and the bevel gear meshes with a gear 41, of suitable 95 diameter, on a shaft 42, which may be connected in any desired manner with an object, whereby the power imparted to the power shaft 30, is transmitted through the shaft 42, to the said object, to exert a drawing or a lifting force, or to produce an oscillating or a reciprocating movement as the case may be; the manner of transmitting power from the shaft 42, being determined by the character of work to be performed. 105

In practice, power is applied to the power end of the initial lever 10, either manually, or through the medium of the crank 14, and its power-driven shaft 15, and this power is transmitted to the lever 19, and thence to the 110 lever 25, the mechanical advantage due to each succeeding lever, being in proportion to the position of the fulcrum of each lever with respect to its opposite ends. The rocking movement of the lever 25, imparts an 115 oscillating movement to the levers 29, by which the groups of ratchet wheels, are alternately engaged, and the shaft 30, is thereby continuously rotated. By arranging the ratchet wheels in the manner before 120 mentioned, there can be no lost motion of the pawls 34, with respect to the ratchet teeth, as one pawl in each group is always in engagement with a tooth.

Having described our invention, what we 125 claim as new and desire to secure by Letters Patent, is:

1. In a machine of the character described, a power shaft, two groups of ratchet wheels rigidly mounted on said shaft, a pair of 130

levers having bifurcated ends, which ends are pivotally mounted on said shaft, each bifurcated end inclosing one group of ratchet wheels, pins extending through said 5 bifurcated ends, pawls mounted on said pins and adapted to engage said ratchet wheels, the teeth of each wheel in each group being out of line with those of the next succeeding wheel, an oscillating lever, links connecting 10 the same on each side of its fulcrum, with the free ends of the bifurcated lever, and means for oscillating said lever. 30

2. In a machine of the character described, a power shaft, two groups of ratchet wheels 15 rigidly mounted on said shaft, the teeth of each wheel in each group being out of line with those of the next succeeding wheel, a pair of levers having bifurcated ends, which ends are pivotally mounted on said shaft,

each bifurcated end inclosing one group of 20 ratchet wheels, pins extending through said bifurcated ends, pawls pivotally mounted on said pins in line with the ratchet wheels and adapted to engage the same, plates secured to said bifurcated levers, having independent 25 integral spring fingers which engage said pawls, an oscillatory lever, links connecting the same on said side of its fulcrum, with the free ends of the bifurcated levers, and means for oscillating said lever. 30

In testimony whereof we affix our signatures in presence of two witnesses.

JOSEPH A. BOZUNG.

PATRICK S. McMAHON.
